UNITED STATES PATENT OFFICE

144,251

DESIGN FOR A LIGHTING FIXTURE GLOBE

James J. Kreidler, Huntington Park, Calif.

Application January 24, 1945, Serial No. 117,560

Term of patent 14 years

(Cl. D48—16)

To all whom it may concern:

Be it known that I, James J. Kreidler, a citizen of the United States, residing at 2705 East Slauson Avenue, Huntington Park, in the county of Los Angeles, State of California, have invented a new, original, and ornamental Design for a Lighting Fixture Globe, of which the following is a specification, reference being had to the accompanying drawing, forming part thereof.

Figure 1 is a side elevation taken from a position directly facing one side of a lighting fixture globe, showing my new design; Figure 2 is a top plan view; Figure 3 is a bottom plan view;

Figure 4 is another side elevation taken from a position facing diagonally a side of the lighting fixture globe; Figure 5 is a sectional view taken transversely on the line 5—5 of Figure 2, and in the direction of the arrows, and Figure 6 is another sectional view taken diagonally on the line 6—6 of Figure 2.

The dominant features of my design reside in the portions shown in full lines.

I claim:

The ornamental design for a lighting fixture globe, as shown and described.

JAMES J. KREIDLER.
